US0D1063328S

(12) United States Design Patent (10) Patent No.: US D1,063,328 S
(45) Date of Patent: * Feb. 25, 2025

(54) SANDAL

(71) Applicant: Birkenstock IP GmbH, Linz am Rhein (DE)

(72) Inventors: Adam Owen, Linz am Rhein (DE); Arno Marchand, Linz am Rhein (DE)

() Term: 15 Years

(21) Appl. No.: 35/518,736

(22) Filed: Sep. 29, 2023

(80) Hague Agreement Data

Int. Filing Date: Sep. 29, 2023

Int. Reg. No.: DM/232247

Int. Reg. Date: Sep. 29, 2023

Int. Reg. Pub. Date: Oct. 20, 2023

(30) Foreign Application Priority Data
